PAPER VENDOR

Earnest B. Crosley, San Diego, Calif.

Application January 29, 1934, Serial No. 708,734

4 Claims. (Cl. 206—38)

This invention relates to new and useful improvements in means for holding, for dispensing or for vending paper wrappers. While the invention may be utilized for various paper wrappers, or possibly even for wrappers which are made of sheet material other than paper, yet the invention is more particularly intended as a holder for cigarette papers and relates to the provision of a device which may be readily attached to tobacco cans and will act as a paper container as well as to hold the papers in such a manner that they may be removed for use one at a time.

Another important object of the invention is to provide for paper wrappers a holder which is constructed in such a manner that it may readily be fitted in a friction tight manner within the lid of a tobacco can without interfering with the opening and closing movements of the lid, and which will safely stay in its operative position until the paper wrappers held therein have all been withdrawn, whereupon the holder may be readily removed and returned to its operative position after refilling; or replaced by another holder filled with the paper wrappers, which the trade has provided for the user.

Still another object of the invention is to provide improved means for causing the packet of wrappers contained in the device to remain in a proper withdrawable condition until all the wrappers in the holder have been withdrawn therefrom.

Yet another object of the invention is to provide, as a new article of manufacture, a container for cigarette wrappers which can be manufactured at a very low cost, supplied with a packet of the wrappers and then possibly furnished gratis to a customer who has purchased a can of tobacco.

Other objects, advantages and features of the invention may hereinafter appear.

Referring to the accompanying drawing which illustrates what is at present deemed to be a preferred embodiment of the invention,

Fig. 1 is a perspective view of a tobacco can showing the same equipped with the invention, the lid of the can being in an open position and portions of said lid being broken away to show underlying structures.

Fig. 2 is a perspective view of a wrapper supporting member provided by the invention, a portion of said holder being broken away in order to show the interior thereof more clearly.

Fig. 3 is a perspective view of the wrapper holding device separately shown, an end portion

thereof being broken away to disclose the arrangement of the wrappers.

Fig. 4 is a perspective view of the wrapper holder showing the same intact and exposing to view the opposite face to that shown in Fig. 3.

Referring in detail to the drawing, the tobacco can 5 is shown provided with a lid 6 hinged thereto and of a well known construction, said lid having the back or outer wall 7, end flanges 8, front flange 9 and hinged flange or extension 10.

The improved wrapper holding device provided by the invention includes an elongated rectangular plate having a body portion 12 which is furnished with end flanges 13 and side flanges 14, said flanges all being directed toward the same 15 face of the plate. At each corner of said plate there is provided a cutaway portion or recess 15 or, in other words, the end and side flanges are shortened sufficiently to leave the space designated at each corner of the plate. The object of 20 providing these spaces 15 is to render the resilient flanges 13 and 14 more bendable in order that they may more readily be wedged into their operative position, as shown in Fig. 1.

The body portion 12 of the holding device is 25 provided preferably at its midwidth with a longitudinal slot 17 through which the paper wrappers may be withdrawn one at a time. Said slot is not necessarily formed by removing any portion of the metal, but may be made by slitting the metal and striking up therefrom the outcurved parallel lips 18. Owing to the protruding character of said lips they aid the user in using his fingers to grasp the wrappers preparatory to withdrawing them. Said lips also form 35 smooth guiding means for the paper wrappers as they are being withdrawn for use.

In Fig. 3 the wrapper holder is shown housing a packet 19 of paper wrappers, and a retaining sheet 21 is shown, said sheet being partly wrapped around the holder and being glued or otherwise adhered thereto along its end edges at opposite sides of the slots 17. The central portion of said sheet 21 overlies the otherwise open back side of the paper holder in order to keep the 40 cigarette papers or other wrappers from displacement. Within the rectangular space designated 22 said sheet is provided with a gummed exterior surface. Owing to this arrangement, when the holder is in place within the lid of the tobacco can, the exterior gummed surface will adhere to the inner face of the back of the lid to aid in keeping the device in place within the lid, but will also hold the packet of wrappers in a more open formation so that they may be 50 55

more readily withdrawn one at a time for use.

It is to be understood that the wrappers 19 will be assembled in pack form in a well known interfolded manner so that each time the front 5 wrapper is withdrawn an edge of the next wrapper will project from the slot 17 where it will be readily accessible to the fingers of the user. The proper delivery of the wrappers one at a time from the housing formed by the two recessed 10 members is further insured by the reason of the fact that the plate 12 is downwardly inclined along the base of each of the lips 18, as best shown in Fig. 1.

It will be seen that when the holder which 15 consists of the plate 12 and its marginal flanges 13 and 14, is fitted friction tight within the flanged portion of the tobacco can, being disposed therein in a reverse manner, that is to say, with its flanged side directed oppositely to the flange 20 of the lid, said holder will combine with the lid to form a housing for containing the interfolded wrappers. It will probably be found most advantageous to make this housing of sheet metal, but it is possible that other rigid sheet material 25 may be used to form at least a part thereof.

I claim:

1. In combination, a can cover made of rigid sheet material, said cover having a body portion provided with side flanges, a housing member 30 consisting of a plate having marginal flanges projecting toward one face thereof, said marginal flanges fitting friction-tight within the flanges of said cover to form a housing between said plate and the body portion of said cover, 35 there being a delivery slot through said plate, a packet of interfolded wrappers within said housing positioned to be withdrawn one by one through said slot, and a retaining strip secured to said housing member and overlying the flanged side thereof to retain said wrappers in place.

2. In combination, a can cover made of rigid

sheet material, said cover having a body portion provided with side flanges, and a housing member consisting of a plate having marginal flanges projecting toward one face thereof, said marginal flanges fitting friction-tight within the flanges of said cover to form a housing between said plate and the body portion of said cover, 5 there being a delivery slot through said plate, the end portions of said flanges being cut away in order to render them more bendable.

3. In combination, a can cover made of rigid sheet material, said cover having a body portion provided with side flanges, a housing member consisting of a plate having marginal flanges projecting toward one face thereof, said marginal flanges fitting friction-tight within the flanges of said cover to form a housing between said plate and the body portion of said cover, 15 there being a delivery opening through said plate, a retaining sheet having gummed opposite edge portions whereby said sheet is adhered to said plate in a position wherein the body portion of the sheet bridges the space between the flanges of said plate, and a packet of interfolded wrappers held in place by said sheet, said 20 wrappers being withdrawable one at a time through said slot, the body portion of said sheet being gummed on its outer side and caused to adhere to the lid rearwardly of the packet.

4. In a device of the kind described, a housing including two recessed members one of which is telescoped into the other with a friction-tight fit, one of said members being slotted to provide a wrapper-delivery opening, a packet of wrappers within said housing for serial delivery through said opening, and a packet-retaining sheet within said housing, said sheet having gummed end portions which are adhered to the slotted face of said slotted member at opposite sides of the slot thereof.

EARNEST B. CROSLEY.
